GRATE SHAKING AND DUMPING DEVICE

Filed Jan. 17, 1930

UNITED STATES PATENT OFFICE

OSCAR P. NYSTROM, OF HOLLAND, MICHIGAN, ASSIGNOR TO HOLLAND FURNACE COMPANY, OF HOLLAND, MICHIGAN

GRATE SHAKING AND DUMPING DEVICE

Application filed January 17, 1930. Serial No. 421,384.

The invention is an improvement upon the grate shaking and dumping device appearing in patent application of James Murchie, filed Feb. 28, 1929, Ser. No. 342,073.

5 The objects of the invention are:

First, to improve the organization of that combination and simplify the arrangement of parts.

Second, to provide an improved connection by the shaking and dumping bar and the shaker arm of the furnace grate.

Third, to provide improved means of rocking the shaker bar.

Fourth, to provide improved base bracket connection.

Objects pertaining to details will definitely appear from the description to follow.

A preferred embodiment of my invention is shown in the accompanying drawings, in 20 which:

Fig. 1 is a detail perspective view of my improved grate shaking and dumping device shown in position on a furnace, parts of the furnace being indicated by dotted lines, 25 and the grate being in operative position.

Fig. 2 is a similar view to that of Fig. 1, showing the grate in dumped position, the grate being shown in full lines.

Fig. 3 is a vertical detail sectional elevation 30 view, somewhat reduced in size, taken on the plane indicated by line 3—3 of Fig. 1.

Fig. 4 is an enlarged detail sectional view on line 4—4 of Figs. 1 and 5.

Fig. 5 is a detail sectional view on the irregular line 5—5 of Fig. 4, showing details of the swivel connection and the dumping lever means.

Parts will be identified by their numerals of reference which are the same in all the 40 views.

1 is the ash pit casing of the furnace in the usual form, indicated by dotted lines. 2 is the flanged doorway or frame. 3 is the dumping grate. 4 is the rocking cross bar on which 45 the grate 3 is pivoted at 5 (see Fig. 3). 6 is the actuating shaker arm secured to the downwardly extending lug 31 on the grate 3 and projecting out to a point which is within the plane of the ash pit door. This 50 arm 6 is oscillated to shake the grate and is

dropped down to dump the grate. The same is shown in operative position in Figs. 1 and 3, and in the dumped position in Fig. 2.

7 is the shaker lever fulcrumed at 71 on the base bracket 8 which is secured to the hinged lug 9 at the side of the ash pit casing. 10 is the reciprocating bar from the lever 7 extending through a hole in the ash pit door frame to couple to the grate shaker bar. This bar is supported at its mid-point by the opening in the said ash pit door frame through which it is adapted to reciprocate. The bar can also be turned on its axis to drop the grate.

The inner end 101 of the bar 10 is formed 65 like a crank and is provided with a shackle 11 which extends into a loop 111 which embraces the said shaker arm 6 so that when the shaft 10 is turned 180°, it drops the shaker arm 6 and tips and dumps the grate, 70 it being possible to shake the grate in the dumped position to freely discharge its contents into the ash pit below.

The outer end of the bar 10 is also carried 75 by a shackle 12 through which it swivels, the same being supported on cross pivot bolt 13, as clearly seen in Figs. 4 and 5.

Bar 10 is provided with a collar 102 to shoulder against the shackle 12 and is retained at its outer end by cross pin 103. The outer 80 end of bar 10 is squared at 104. Turning lever 14 is slotted at 141 and engages the squared portion 104 of the bar 10. This turning arm is also provided with a handle 142 and with a pair of engaging lugs 143 which 85 embrace the lever 7 above or below, depending on the position to which it is adjusted.

The lever 14 is provided with segmental projections 144 each side of the slot 141 to seat against the shackle 12 and permit the 90 rocking movement when the grate is being shaken.

From this description it will be seen that when the device is in the position illustrated in Figs. 1 and 2, the adjusting arm 14 is locked in the upper position by its lugs 143 each side of the lever 7 and the grate can be rocked back and forth by manipulating the handle which carries the bar 10 out and in 95 through the opening in the frame, shaking 100 the grate.

the grate all that is ordinarily required. If, for any reason, it is necessary to dump the grate, as because of an accumulation of clinkers or the like, the rocker arm 14 is pulled 5 away from engagement with the lever 7 and the bar 10 is turned 180° and rocked in that position. As it turns over, the shackle 11 drops down and the grate is dumped to the position indicated in Fig. 2. The shaker 10 may be operated in this position to completely dump the grate.

I desire to state that my improved structure can be considerably modified without departing from my invention. I desire to claim 15 the same specifically and also broadly as pointed out in the appended claims.

Having thus described my invention, what I claim as new and desire to secure by Letters Patent, is:

20 1. In a grate shaking and dumping device, the combination with the ash pit casing, of a dumping grate therein having a shaker arm, a base bracket outside of said casing, a vertically slotted shaker lever fulcrumed on the 25 said base bracket, a reciprocating grate shaker bar having a crank arm formed on its inner end and squared at its outer end disposed to reciprocate through an opening in the side of the ash pit door frame, a slotted shackle 30 embracing the said shaker arm and pivoted to the said crank on the said grate shaker bar, a shackle disposed in the vertical slot in said shaker lever journalled on the outer end of said shaker bar and a cross pivot bolt in the 35 slot in said lever for pivotally supporting said shaker bar, a dumping lever slotted to embrace the squared end of the said shaker bar to turn the same up or down, and engaging lugs on said dumping lever to engage the said 40 shaker lever and secure the said bar in up or down position.

2. In a grate shaking and dumping device, the combination with the ash pit casing, of a dumping grate therein having a shaker arm, a base bracket outside of said casing, a vertically slotted shaker lever fulcrumed on the said base bracket, a reciprocating grate shaker bar having a crank arm formed on its inner end and squared at its outer end disposed to reciprocate through an opening in the side of the ash pit door frame, a slotted shackle embracing the said shaker arm and pivoted to the said crank arm on said grate shaker bar, a shackle disposed in the vertical slot in said shaker lever journalled on the outer end of said shaker bar and a cross pivot bolt in the slot in the said lever for pivotally supporting said shaker bar, and a dumping lever slotted to embrace the squared end of the said shaker 60 bar to turn the same up or down.

3. In a grate shaking and dumping device, the combination with the ash pit casing, of a dumping grate therein having a shaker arm, a vertically slotted shaker lever, a reciprocating grate shaker bar having a crank

arm formed on its inner end disposed to reciprocate through an opening in the side of the ash pit door frame, a slotted shackle embracing the said shaker arm and pivoted to the said crank arm on said grate shaker bar, 70 a shackle disposed in the vertical slot in said shaker lever journalled on the outer end of said shaker bar and a cross pivot bolt in the slot in said lever for pivotally supporting said shaker bar, and a dumping lever slotted 75 to embrace the squared end of the said shaker bar to turn the same up or down.

4. In a grate shaking and dumping device, the combination with the ash pit casing, of a dumping grate therein having a shaker arm, 80 a vertically slotted shaker lever, a reciprocating grate shaker bar having a crank arm formed on its inner end disposed to reciprocate through an opening in the side of the ash pit door frame, and means to turn said 85 shaker bar up or down.

In witness whereof I have hereunto set my hand.

OSCAR P. NYSTROM.
